UNITED STATES PATENT OFFICE.

ASA W. FARNEY, OF CLAY COUNTY, MISSOURI.

REVETMENT.

Application filed January 31, 1927. Serial No. 164,822.

This invention relates to dikes for use in changing the direction of the current of a stream and also to prevent erosion of the bank and bottom of a stream, and has as its chief object the production of a new, efficient and inexpensive method of insuring the proper and permanent connection between certain screen poles forming a part of the dike and a mat which is sunk to the bottom 10 of the stream.

With all methods heretofore used, more or less difficulty has been encountered in insuring the permanent fastening of the screen poles to the mat as it has heretofore been 15 the custom to drive the screen poles through the mat after the latter had been sunk to the bottom of the stream. The poles soon work loose and the current swings them upwardly or breaks them off and entirely destroys the efficiency of the dike.

With the general object named in view, the invention consists in certain novel and useful features of construction as hereinafter described and claimed; and in order that 25 it may be fully understood reference is to be had to the accompanying drawings, in which:

Figure 1 is a top plan view of a dike constructed in accordance with the invention 30 as it will appear before the mat has been weighted.

Figure 2 is an enlarged section on the line II—II of Figure 1 with the upper part of the piling and screen poles broken away.

Figure 3 is an end view of the construction before the mat has been sunk to illustrate the position of the screen poles.

Figure 4 is a view similar to Figure 3 after the mat has been sunk by suitable weights.

In the said drawings where like reference characters identify corresponding parts in all of the figures, A, B, and C indicate each row of a series of parallel rows of piles 1 which are permanently driven into the bed of 45 the stream. The row A indicates the row of piling on the upstream side, and the row C, the row of piling on the downstream side, it being understood however, that any number of rows of piling may be utilized according 50 to the force of the current and other natural conditions to be anticipated. The rows of piling are braced longitudinally and laterally respectively by suitable braces 2 and 3 bolted or otherwise securely fastened in position, the lowermost row of braces being secured as close to the water line at the time

of construction as possible. In order to strengthen the structure, a series of diagonal braces 4 is inclined downwardly from adjacent the upper ends of piles of row A to 60 adjacent the water line of the piles of row C. A mat 5 of the desired area is now woven in position on the surface of the water, the mat at opposite sides of the dike being woven on a barge and fed off the 65 upstream end as common in the art, and the portions of the mat between the piles 1 being woven by men working from platforms supported by the lateral braces 3 as will be readily understood.

In carrying out the invention, a series of tie poles 6 are laid along the surface of the mat 5 and are tightly secured thereto adjacent the upstream side of the row of piles C, so that the force of the current tending to loosen the tie poles will be resisted by abutment of the poles against the row of piles. The larger ends of a series of screen poles 7 of sufficient length to reach from the bottom of the stream to the uppermost row 80 of braces 2, are now driven through the mat as illustrated in Figure 2, said poles being substantially equally spaced apart, and each being nailed and securely wired to the tie poles 6 as shown at 8. It will be evident that the screen poles while in this position will project some distance above the tops of the piling, and in order to space the upper ends of said screen poles to hold them in proper position until the mat has settled to the bottom of the stream as will hereinafter appear, a series of horizontal spacers 9 are nailed to each section of the screen between adjacent lateral rows of piling, it being understood 90 that the connection between each screen pole and the spacers is preferably by a single nail in order to allow for irregularities in the surface of the screen upon the sinking of the mat.

The mat is now gradually weighted by 100 piling stone 10 or the like thereon, commencing with the upstream edge of the mat and working downstream as is common in the art. It will be evident that the mat will carry the screen poles down with it, and through the spacers that the screen poles will approximately maintain their proper distances apart. The weight of the mat will force the protruding ends of the screen poles into the bed of the stream and the mat will 105 finally settle permanently on the bottom. The upper ends of the screen poles then abut

against the upper row of braces 2 and after the mat has permanently settled, said ends of the poles are nailed securely in position as shown at 11 in Figure 4.

5 It will be apparent that with the method of construction described in this application, the permanent securing of the ends of the screen poles to the mat is absolutely insured, and it is to be understood that while I have 10 described and claimed the preferred embodiment of the invention, I reserve the right to make all changes properly falling within the spirit and scope of the appended claims.

I claim:

15 1. The process of producing a dike in a stream, comprising the driving of a plurality of rows of spaced upright piles into the bed of the stream, the weaving of a mat around and between said piles, the securing 20 of the lower ends of a line of screen poles to said mat in upright position and spaced relation, and the submersion of the mat and lower ends of the screen poles to the bed of the stream.

25 2. The process of producing a dike in a stream, comprising the driving of a plurality of rows of spaced upright piles into the bed of the stream, the weaving of a mat around and between said piles, the placing 30 of a tie pole horizontally on said mat against the upstream side of a row of said piles, the securing of the lower ends of screen poles to said tie pole in upright position and spaced relation, and the submersion of 35 said mat, tie pole and the lower ends of the screen poles to the bed of the stream.

3. The process of producing a dike in a stream, consisting in driving parallel rows 40 of piles into the bed of the stream, the production of a mat on the water around the piles and at opposite sides of the rows of piling, the placing of tie poles horizontally 45 on the mat against the upstream side of the downstream row of piles, the connecting of the piles of the downstream row at the upstream sides thereof by longitudinal braces near the surface of the water and in a higher plane, the placing of a row of screen poles 50 through the mat and against the inner side of said braces and tie poles, the fastening of the mat to the tie poles and the screen poles to the latter, the securing of the upper

parts of the screen poles in spaced relation, the sinking of the mat, tie poles and screen poles to the bed of the stream, and the fastening of the screen poles to the piling structure to retain said poles in depressed position.

4. A dike comprising a plurality of rows of piling, braces connecting the piles, a weighted mat on the bottom of the stream through which the piles extend, horizontal tie poles upon the mat and against the upstream side of a row of the piling, and a row of screen poles bearing against the upstream side of braces connecting the piles of said row and against the corresponding side of the tie poles, and impaling and projecting through the mat.

5. A dike comprising a plurality of rows of piling, braces connecting the piles, a weighted mat on the bottom of the stream through which the piles extend, horizontal tie poles upon the mat and against the upstream side of a row of the piling, a row of screen poles bearing against the upstream side of braces connecting the piles of said row and against the corresponding side of the tie poles, and impaling and projecting through the mat, means spacing the upper ends of the screen poles, means for fastening the upper ends of the screen poles to the upper part of the piling structure and wire woven spirally around the tie poles and through the mat for fastening them together.

6. A dike comprising a plurality of longitudinal rows of piling suitably spaced apart, longitudinal and cross braces connecting the piles, a weighted mat on the bottom of the stream through which the rows of piles extend, horizontal tie poles arranged upon the mat and against the upstream side of a longitudinal row of the piles, a longitudinal row of closely spaced upright screen poles bearing against the upstream side of the longitudinal braces for the said row of piles and against the corresponding side of the said tie poles, and impaling and projecting through the mat into the bed of the stream, and means extending through the mat and around the tie poles to fasten them together.

In witness whereof I hereunto affix my signature.

ASA W. FARNEY.
